Primary Examiner — Jeffrey D Asch(74) *Attorney, Agent, or Firm* — Hemisphere Law, PLLC; Zhigang Ma(57) **CLAIM**

The ornamental design for an intelligent communication terminal, as shown and described.

DESCRIPTION

FIG. 1 is a perspective view of an intelligent communication terminal showing my new design;

FIG. 2 is another perspective view seen from the back side thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines illustrate portions of the intelligent communication terminal that form no part of the claim design.

1 Claim, 8 Drawing Sheets(56)
